UNITED STATES PATENT OFFICE

WILLIAM H. BERGER, OF PHILADELPHIA, PENNSYLVANIA.

DESIGN FOR A GAS-PIPE BAND.

SPECIFICATION forming part of Design No. 19,673, dated March 4, 1890.

Application filed December 31, 1889. Serial No. 335,556. Term of patent 14 years.

To all whom it may concern.

Be it known that I, WILLIAM H. BERGER, a citizen of the United States, residing at Philadelphia, in the county of Philadelphia and State of Pennsylvania, have invented a certain new and useful Design for Gas-Pipe Bands; and I do hereby declare the following to be a full, clear, and exact description of the invention, reference being had to the accompanying drawings, which form part of this specification.

This invention has relation to designs for gas-pipe bands; and it consists in a gas-pipe band having the surface ornamentation hereinafter described, and shown in the accompanying drawings, in which—

Figure 1 is a front view, and Fig. 2 a side view, of a gas-pipe band embodying my design. Fig. 3 is a sectional view.

The design, in its essential features, consists in an arch A, with ears B, pierced for

the passage of fastening-screws, and with a projecting ridge or band C, terminating in small circular beads or flanges d, surrounding the screw-holes.

The design exhibits the following features: the arched band, with the plain or unbeaded portion on either side of the bead C, and the plain surfaces d', from which rise the beads d and the bead C. The latter may be surface-ornamented according to taste.

What I claim as new, and desire to secure by Letters Patent, is—

The design for a gas-pipe band or strap, as shown and described.

In testimony that I claim the foregoing I have hereunto set my hand this 11th day of December, 1889.

WILLIAM H. BERGER.
